UNITED STATES PATENT OFFICE.

SALLY AIRO, OF DETROIT, MICHIGAN, ASSIGNOR TO LINCOLN MANUFACTURING COMPANY, OF DETROIT, MICHIGAN, A CORPORATION OF MICHIGAN.

DESIGN FOR A BRACKET BACK FOR LIGHTING FIXTURES.

Application filed January 2, 1926. Serial No. 15,940. Term of patent 7 years.

To all whom it may concern:

Be it known that I, SALLY AIRO, a citizen of Finland, residing at Detroit, county of Wayne, State of Michigan, have invented a new, original, and ornamental Design for Bracket Backs for Lighting Fixtures, of which the following is a specification, reference being had to the accompanying drawing, forming part thereof.

Figure 1 is a front elevation.

Fig. 2 is a side elevation.

Fig. 3 is a bottom elevation.

Fig. 4 is a horizontal section taken on line A—A, Fig. 1.

I claim:

The ornamental design for a bracket back for lighting fixtures, as shown.

SALLY AIRO.
